UNITED STATES PATENT OFFICE.

MILO HERRICK SPAULDING, OF BOZEMAN, MONTANA.

INITIATING APPARATUS.

Application filed April 15, 1924. Serial No. 706,729.

My invention relates to new and useful improvements in initiating apparatus and more particularly to what may be termed and is commonly known as a combination 5 keystone hoist and electric thunderbolt discharge, the primary object of the invention residing in the construction of such a device that may be used in connection with a lodge room arch so that a keystone or similar 10 emblem may be raised into position at the top or over the arch and at the proper time a member may be ignited and released so as to set off or discharge incense held in a receptacle at a point removed from the arch.

15 A further object of the invention resides in the provision of a slide which carries material adapted to be saturated with alcohol or other suitable ignitable fluid, said material adapted to be ignited upon the closing 20 of an electric circuit and the slide released from its connection to a suitable support to travel, on a guide, to the receptacle containing the incense.

Another object consists in forming the 25 slide in a novel manner whereby it may be received upon an inclined guide-way and, as has been stated, receive cotton or similar material which is adapted to be saturated with alcohol or similar ignitable fluid.

30 With the above and other objects in view, which will appear as the description proceeds, my invention consists in the novel details of construction and arrangement of parts described in the following specification, and illustrated in the accompanying drawings, and while I have illustrated and described the preferred embodiments as they 35 now appear to me it will be understood that such changes may be made as will fall within the scope of the appended claims.

In the drawings:

Fig. 1 is a front elevation of an arch showing the keystone in position.

Fig. 2 is a side elevation of the arch and 45 its associated parts with parts shown in section.

Fig. 2a is a top view of the keystone.

Fig. 3 is a detail showing a rear elevation 50 of the insulating block and its associated parts.

Fig. 4 is a plan of the slide.

Fig. 5 is a vertical section through the slide with parts shown in elevation.

Fig. 6 is an elevation of a modified form 55 of device for attaching a keystone to its supporting cable.

Figs. 7 and 8 are combined side elevations and top plans of further modified forms of keystone connecting means.

Fig. 8a is a sectional detail through the 60 connecting means illustrated in Fig. 8, and

Fig. 9 is a combined elevation and plan of a slightly modified form of means for attaching the magnesium ribbon to its insulating block.

In the drawings 1 indicates a portion of an arch to which a support 2 is adapted to be connected by means of the brackets 3. The bracket 3 consists of a wooden framework, as shown, attached to the back of the arch and the lower end of the support 2 is received therein. The bracket is provided with a bottom piece upon which the lower end of the support 2 rests, the said bottom piece acting as a stop for the support. The support 2 has, at the top, a horizontally extending arm 4 which reaches over the top of the arch and carries a pulley 5. A rope or cable 6 passes over the pulley and to one end of this rope or cable is connected a keystone 7 which is adapted to be raised or lowered upon manipulation of the rope or cable. The keystone is preferably provided in its upper surface with the slot 8 adapted to receive the lower end of a rod 9 said rod 9 having the enlargement 10 on its lower end and the eye 11 at its upper end. The rope or cable 6 will be secured to the eye 11.

A porcelain insulating block 12 is secured to the back of the support 2 and is provided at opposite ends with the brass blocks 13 which carry the rods 14 to which are secured binding posts or clips 15. Connected to the binding posts or clips 15 and spanning the space therebetween is a magnesium ribbon 16 which is preferably knicked at its central point as indicated at 17 for a purpose which will be later described. An electric cord 18 has one of its wires connected to each of the brass blocks 13 and the opposite end of the cord is connected to a switch 19, of any suitable type, but preferably of the snap type.

A brass rod 20 projects from the porcelain insulating block 12 and carries the hook member 21 to which is secured one end of a wire 22, the opposite end of the wire being received in a pot or receptacle 23 adapted to contain incense. The pot or receptacle will be supported on a table or other suitable object 24.

A slide is slidably mounted upon the guide

wire 22. This slide is indicated generally at 25 and comprises a tubular hub portion 26 from which extend the arms 27 formed of wire or other suitable material. The arms 5 are provided at their outer ends with depressions 28 in which are received cotton 29 or other suitable material, said cotton or material extending circumferentially of the guide and forming the outer rim thereof. The cotton 10 or other material will be saturated with alcohol or other ignitable fluid. One of the arms 27 is formed with the hook 30 to which will be secured one end of a magnesium ribbon 31, the opposite end of the ribbon 31 15 engaging the magnesium ribbon 16 to hold the slide 25 in position adjacent the upper end of the guide wire 22.

In Fig. 6 I have shown a slightly modified form of device for connecting the keystone 20 7 to the rope or cable 5. This consists of a vacuum cup 32 which is adapted to be connected to the rope or cable by means of the hooked wire or rod 33, the vacuum cup 34 25 engaging the upper surface of the keystone.

In Fig. 7 I have illustrated a still further modified form of means for connecting the keystone to the rope or cable, this means 30 35 being in the form of a quarter turn screw 34. The threaded portion of the quarter turn screw 34 is received in an interiorly threaded plug 35 which is inserted in the keystone.

In Fig. 8 I have shown another form of connecting means between the keystone and the rope or cable. In this form of connection a plug 36 is inserted in the top of the keystone and has a bayonet slot 37 to receive the projections 38 carried by the rod or link 39 having the eye 40 at the upper 40 end.

In Fig. 9 I have shown a slightly modified form of means for attaching the magnesium ribbon 16 to the clips 15 carried by the rods 14. In this form of the invention 45 the magnesium ribbon is carried by a cardboard or fibre support 41, the magnesium ribbon being attached to said support by means of brass clips 42. The cardboard or fibre support will be engaged by the clips 50 15 and the magnesium ribbon thus held in place.

From the above detail description it is thought that the construction of my device will be clearly understood and I will now 55 proceed to describe more in detail the manner of using. With the arch in position the keystone is connected to the rope or cable 6 and then raised by pulling upon said rope or cable, it being understood that the support 2 has previously been connected to the arch by means of the brackets 3. The slide 60 25 is then placed in position upon the guide wire 22, by passing said wire through the

hub portion 26 and the slide will be raised upon said guide wire and held in such position by means of the magnesium ribbon 31 which engages the magnesium ribbon 17. Prior to placing the slide upon the wire the cotton or other similar material 29 will have been saturated with alcohol or similar ignitable fluid. As has been previously stated the lower end of the guide wire will extend into the receptacle 23 containing the incense. During the initiation ceremonies the lights will be extinguished and at the desired time, 75 during the ceremonies, the switch 19 will be closed and this will cause a current to pass through the cord 18 and ignite the magnesium ribbon 16 which in turn will ignite the magnesium ribbon 31 and the cotton or other material 29 carried by the slide. The ribbon 15 being notched or knicked at 17 will fire at this point first and the igniting of the ribbon 31 will release the slide 25 which will be in flames and allow it to pass down the 85 receptacle 23.

Having fully described my invention what I claim as new and desire to secure by Letters Patent is:

1. A device of the character described including a support, transversely spaced rods carried by the support, an ignitable member connecting the spaced rods, a guide connected to the support, a slide mounted on the 95 guide, means engageable with the ignitable member for supporting the slide, and means for igniting the ignitable member for allowing the slide to drop on the guide.

2. A device of the character described including a support, transversely spaced rods carried by the support, an ignitable member connecting the spaced rods, said ignitable member being weakened intermediate its ends, a guide connected to the support, a 100 slide mounted on the guide, means engageable with the ignitable member for supporting the slide, and means for igniting the ignitable member for allowing the slide to drop on the guide.

3. A device of the character described including a support, an insulating block carried by the support, transversely spaced rods carried by the insulating block, an ignitable member connecting the spaced rods, a guide 115 connected to the support, a slide mounted on the guide, means engageable with the ignitable member for supporting the slide, and means for passing a current of electricity through the rods to ignite the ignitable member for allowing the slide to drop on the 120 guide.

In testimony whereof I hereunto affix my signature.

MILO HERRICK SPAULDING.
